CONTROLLING MEANS FOR ATTAINING EQUAL SPEEDS OF TWO PISTONS WORKING AGAINST RESISTANCES

Emil Biernath, Stuttgart-Unterfinkheim, Germany, assignor to Schloemann Aktiengesellschaft, Dusseldorf, Germany

Application June 11, 1958, Serial No. 741,322

Claims priority, application Germany June 13, 1957

3 Claims. (Cl. 60—52)

In so-called double-billet extrusion presses, for example, there is the problem of so controlling two pistons, which are each advanced by a hydrostatic pump against resistance, in such a way that they travel the same distances per unit of time, independently of the magnitude of the resistances opposing them. Even if the two pumps always revolve at the same speed, which is attainable in a simple manner by coupling the pump shafts together for instance, the desired aim is attained only approximately, but, from various causes, not with the necessary precision, for instance because the losses in the pumps and in the hydraulic drives of the two pistons differ from one another in magnitude when the resistances opposing the movements of the pistons are different.

This invention starts from a controlling means for the attainment of equal speeds of two pistons working against resistance, which are each driven by a hydrostatic pump provided with continuously variable means for regulating the quantity delivered. The invention consists in the feature that the branch, leading to one of the two pumps, of the delivery-regulating means common to the two pumps, can be corrected in dependence upon the difference between the speeds of the two pistons. The desired correction on one of the two branches of the delivery-regulating means admits of being accomplished in a very simple manner by the aid of mechanical means, by the delivery-regulating means acting through a rockable lever in each case upon the adjusting appliances of the two pumps, the effective lengths of the arms of one lever being variable relatively to the effective lengths of the arms of the other lever. The adjusting of the lever-arm lengths of one lever may be effected by an adjusting motor that can be started forwards and backwards, and that can in its turn be started in one direction of rotation or the other, or stopped, by an electrical relay. The controlling of the motor may however alternatively be effected by mechanical means in dependence upon an appliance measuring the differences between the speeds of the pistons.

As already mentioned above, the controlling means according to the invention is adopted with special success when the two pump shafts are coupled together, for instance when they are driven by a common motor. In this case the correcting appliance serves merely to correct the differences between the quantities delivered by the two pumps at the same speeds of revolution.

The invention is illustrated by way of example in the accompanying drawing.

In a press frame 1, pistons 2 and 3 are movable in cylinders 8 and 9. They can be acted upon by liquid, which is delivered into the working cylinders 8 and 9 through pipes 4 and 5 respectively by hydrostatic pumps 6 and 7. The pistons 2 and 3 are connected with slides 10 and 11, which are carried by press rams 12 and 13 respectively, the even running of which is to be ensured by this invention.

The press head 14 has a bore 15, into which the two rams 12 and 13 can enter, for the purpose of extruding through a die 16 the extrusion material located in the

2

bore 15. For the measurement of the difference in speed between the two pistons 2 and 3 the slides 10 and 11 each carry a toothed rack, 17 and 18 respectively, between which is arranged a pinion 19, which in its turn is rotatably supported on an arm 20. This arm is pivoted at 21 to a lever arm 22, which is rockable about a fixed fulcrum 23. The upper end of the lever arm 22 is pivoted at 24 to a rod 25, the other end of which is pivoted at 26 to a voltage-collector 27, which is rockable about a fixed fulcrum 28, which is connected by a conductor 34 with a relay 35. The free end of the voltage-collector 27 is movable over an arcuate resistance R₁, the ends of which are connected by conductors 32 and 33 with the ends of a resistance R₂, along which a voltage-collector 36 is movable. Between the two conductors 32 and 33, and therefore between opposite ends of each of the resistances R₁ and R₂, a potential difference is established by a source of voltage such as a battery 29, connected with the said conductors by leads 30 and 31.

In the drawing the two voltage-collectors 27 and 36 occupy their mid positions, marked O. From the relay 35 a conductor 35a leads to a control switch 38, which, according to the voltage transmitted to it, causes an adjusting motor 40, by way of a controlling conductor 39, to start in one direction or the other. When the relay 35 is under zero voltage it stops the motor 40 through the relay 38.

The adjusting motor 40 receives current through conductors 41 from a source of current, and drives, with its shaft 42 through a slipping clutch 42a, a worm 43, which in its turn cooperates with a worm wheel 44. On the shaft 45 of the worm wheel 44 is mounted a toothed wheel 46, which meshes with an axially displaceable rack 47. Abutments 59 and 59a, which may also be adjustable in the direction of the rack 47, limit the upward and downward movement of the rack. When the rack 47 strikes one of these abutments, the clutch 42a slips. Upon the rack is securely mounted a rocking bearing 48, in which a control lever 49 can rock. Upon displacement 40 of the rack 47 the bearing 48 is displaced along the lever 49, so that the effective lengths of the arms 49a and 49b of that lever are altered. The upper end of the lever arm 49a of the lever 49 is attached to an adjusting rod 50 of the pump 7, while to the lower end of the arm 49b is attached a control rod 51. At the point 51a of the control rod is attached a mechanical appliance, not shown, for regulating the quantity delivered by the pumps 6 and 7. The rod 51 can however also be displaced by hand. To the other end of the control rod 51 is pivoted the lower arm 52a of an adjusting rod 52, the upper arm 52b of which is in its turn pivotally engaged at 53 with the adjusting rod 54 of the pump 6. The adjusting rods 50 and 54 are not designed as mirror images of one another but are so constructed that the quantities delivered by the two pumps are increased for example when the two adjusting rods 50 and 54 are displaced towards the right. At zero delivery of the pumps the members 54/50, 49, 52 and 51 form a rectangle, as shown in the drawing, and no adjustment of the pump 7 takes place in this position by displacement of the bearing 48. The rocking bearing 55 for the lever 52 is undisplaceable. The two pumps 6 and 7 are driven by a common motor 56, through fixed couplings 57 and 58.

The apparatus works in operation as follows: When pressing is to be effected, the motor 56 is started, and the rod 51 is displaced longitudinally, so that the two pumps 6 and 7 are driven at the same speed of revolution, and the pistons 2 and 3 are advanced at approximately the same speed. With the pistons 2 and 3 move the racks 18 and 17, between which rolls the pinion 19; and it rolls without moving the rod 20 so long as the advance of the pistons 2 and 3 remains equal. If however the piston 3

lags behind the piston 2, the pinion 19 pushes the rod 20 towards the right, as a result of which the rod 25 is displaced towards the left, and the voltage-collector 27 is thereby turned in a counter-clockwise direction. So long as the voltage-collectors 27 and 36 remain in the zero position, the relay 35 remains de-energized. Since however the voltage-collector 27 is now displaced along its resistance R_1 , while the voltage-collector 36 remains in its mid-position, a potential acts upon the relay 35 in such a manner that it controls the switch 38 to start the adjusting motor 40. By the running of the adjusting motor the rocking bearing 48 is displaced, so that the ratio between the lever arms 49a and 49b is altered. Since the rod 51, during the pumping work, is not located in its mid-position as shown, there occurs, owing to the displacement of the rocking bearing 48, an axial displacement of the adjusting rod 50 of the pump 7, which now occasions an increased delivery from the pump 7 into the cylinder 9 of the piston 3. In consequence of this increased delivery, the speed of the piston 3 increases until it has overtaken the piston 2. Under these circumstances the voltage-collector 27 is at the same time turned back by way of the members 17 to 25, so that the relay 35 becomes de-energized, and stops the adjusting motor 40. Since, with the adjusting of the rocking bearing 48, the position of the voltage-collector 36 upon the resistance R_2 has changed, the relay 35 is placed under voltage in the opposite direction, so that it starts the motor 40 in the opposite sense, and this motor now brings the adjusting bearing 48 back into its initial position.

By the abutments 59 and 59a the quickness of the regulating can be limited to a greater or less extent, that is to say, the speed with which the lagging ram, for instance 13, overtakes the leading ram 12, can be restricted. This is important in cable-sheathing presses, since a too rapid overtaking would result in a poor extrusion product.

In cable-sheathing presses with a low extrusion speed, small deliveries are required of the pumps. If with a small pump delivery the voltage-collector 27 has a large deflection, the regulating, that is to say, the acceleration of the lagging ram, need not be effected so rapidly as with a large pump delivery. The regulating operation must therefore be dependent upon existing speed of extrusion. If for instance with a large pump delivery, that is to say, with a high speed of extrusion, a difference of 2 percent between the speeds of the two rams is regarded as admissible, then with a low speed of extrusion the difference in speed in the regulating should not be greater. This is approximately attainable with the controlling means according to the present invention.

This example of construction may advantageously be modified in such a way that not only the bearing 48 but also the bearing 55 is longitudinally displaceable. The appliance effecting this must then be so constructed that one bearing is displaced downwards while the other bearing is displaced upwards.

I claim:

1. Controlling means for equalizing the speeds of two hydraulic pistons working against resistances, for instance the pistons of a hydraulic double-billet extrusion press, comprising: two hydrostatic pumps, each supplying pressure liquid to one of the pistons, two adjusting elements, one for each pump, for continuously varying the quantity of liquid delivered by the pump, a manually movable member, two levers, each connecting one of the adjusting elements with one end of the manually movable member, two bearings, constituting the fulcra of the two levers, one of these bearings being slidable along its lever, these levers being rockable about their fulcra in such a way that when the manually movable member is moved longitudinally in one direction it acts upon the adjusting elements so as to increase the delivery of both pumps, and when it is moved in the opposite direction it acts so as to reduce the delivery of both pumps, and a control acting upon one of the adjusting elements by sliding the fulcrum of its lever along the lever, so as to change the ratio between the effective arms of the lever in dependence upon the difference in speed between the piston associated with that lever and the other piston.

2. Controlling means for equalizing the speeds of two hydraulic pistons as claimed in claim 1, the control that acts upon one of the adjusting elements comprising: two electrical resistances, conductors connecting the ends of one resistance with the ends of the other resistance, a source of voltage interposed between the two conductors, 25 a voltage take-off control movable along one of the resistances, means actuated by any difference in speed between the two hydraulic pistons for moving the control along the resistance, a reversible electric control motor, a relay controlled by current flowing in the conductors, this relay 30 controlling the electric control motor, transmission means 35 by which the electric control motor slides the movable bearing along its lever, a voltage take-off carried by the movable bearing and movable along the second resistance, and means controlled by this voltage take-off for restoring the movable bearing to its normal position when the lagging piston has overtaken the leading piston.

3. Controlling means for equalizing the speeds of two hydraulic pistons as claimed in claim 2, further comprising: abutments limiting the travel of the movable bearing, and a slipping clutch interposed in the transmission 45 means between the electric control motor and the movable bearing.
